UNITED STATES PATENT OFFICE.

VINCENT C. MICKLER, OF ALBANY, GEORGIA.

WIRE STRETCHER.

Application filed April 14, 1923. Serial No. 632,120.

To all whom it may concern:

Be it known that I, VINCENT C. MICKLER, a citizen of the United States, residing at Albany, in the county of Dougherty and

5 State of Georgia, have invented certain new and useful Improvements in Wire Stretchers, of which the following is a specification, reference being had to the accompanying drawings.

10 This invention relates to wire stretchers and more particularly to a wire stretcher for use in stretching the wires of pole lines.

An important object of the invention is to provide a device of this character which 15 may be used for taking up slack in telephone and telegraph lines without interrupting the service thereon.

A further object of the invention is to provide a device of this character which may 20 be very cheaply produced, which is simple in its construction and which will be durable and efficient in service.

These and other objects I attain by the 25 construction shown in the accompanying drawings, wherein for the purpose of illustration is shown a preferred embodiment of my invention and wherein:—

Figure 1 is a perspective view of a 30 stretcher constructed in accordance with my invention; and

Figure 2 is a longitudinal sectional view therethrough.

Referring now more particularly to the drawings, the numeral 10 indicates an inverted U-shaped frame the arms of which are provided with pairs of aligned openings through which are rotatably directed horizontal shafts 11, 12 and 13. The shaft 13 is arranged immediately adjacent the lower 35 ends of the arms and has mounted thereon between the arms a drum 14, preferably formed of hollow sheet metal, and having at one end thereof a ratchet 15 and at the opposite end thereof a gear 16. Upon the 40 shaft 12, which is arranged immediately above the shaft 13 between the arms, a gear 17 is mounted which meshes with the gear 16 of the drum 14. The outer end of the shaft 12 has mounted thereon a second gear 18, which is engaged by a gear 19 secured to the outer end of the shaft 11. The outer extremity of this shaft projects beyond the outer face of this gear and is formed to provide a square shank 20 for engagement 45 by a removable operating handle 21. The shaft 10 is provided at the opposite face

5 of the arm of the U-shaped member against which the gear 19 abuts with a stop collar 22 which prevents its shifting within the frame.

At the lower ends of the arms of the U-shaped member at each side of the shaft 13 are secured the ends of the arms 23 of U-shaped members having formed in the bight portions thereof openings 24. The drum 14 has formed therethrough between the ratchet and gear thereof an opening 25 and an electrical conductor 26, preferably of flexible steel cable, passes through the openings 24 of the bight portions of the U-shaped 60 guide members and through the opening of the drum. The ends of this conducting element are provided with conducting attaching clips 27 which are removable and which may be employed to secure the ends of this 65 cable to a wire from which slack is to be removed. It is pointed out that when the conducting clips 27 are secured to the wire the cable 26 is placed in parallel with the wire and accordingly when by operation of the 70 device the slack has been taken up from the wire this slack may be removed and the wire spliced without interrupting communication over the wire. In order to hold the 75 drum against rotation a pivoted dog 28 is secured to one of the arms 23 of one of the U-shaped guide members for coaction with the ratchet 15 of the drum 14 and may be 80 swung into place when the slack has been removed from the wire to hold the drum 85 against rotation during the splicing operation. When the slack is to be taken from the wire in but a single direction the removable clip 27 at one end of the conducting element 26 is removed and this end of the 90 conducting element knotted to prevent its 95 passage through the opening 25 of the drum.

In the foregoing it is believed to be obvious that by the use of the device constructed in accordance with my invention, slack 100 may be removed from pole lines without interrupting communication thereover. It will furthermore be obvious that the structure hereinbefore set forth is capable of some change and modification without materially departing from the spirit of my 105 invention and I accordingly do not limit myself to such specific structure except as hereinafter claimed.

I claim:—

1. A device for stretching pole lines to remove slack therefrom without interrupt-

ing service over the line being stretched, including a support, a drum rotatably mounted in said support, guides extending at opposite sides of the drum and attached 5 to the support, openings formed in said guides and drum, and a conducting element directed through the openings of the guides and drum and provided at its ends with means whereby it may be electrically connected with the pole line.

2. In a wire stretcher, an inverted U-shaped frame, a drum rotatably mounted between the lower ends of the arms of the

frame, U-shaped guide members secured to the arms of the frame at opposite sides of the drum and provided in their bight portions with openings, an opening through the drum, and a conducting element directed through the openings of the guide members and drum and provided at its ends with 15 clips for electrically connecting the same to a pole line.

In testimony whereof I hereunto affix my signature.

VINCENT C. MICKLER.
